UNITED STATES PATENT OFFICE

148,967

DESIGN FOR A BOBSLED

Ralph Warrender, Sharon, Pa.

Application June 3, 1946, Serial No. 130,350

Term of patent 14 years

(Cl. D34—15)

To all whom it may concern:

Be it known that I, Ralph Warrender, a citizen of the United States, residing at Sharon, in the county of Mercer and State of Pennsylvania, have invented a new, original, and ornamental Design for a Bobsled, of which the following is a specification, reference being had to the accompanying drawing, forming a part thereof.

Figure 1 is a side elevation of the bobsled, showing my new design.

Figure 2 is a top plan view of the bobsled, showing my new design.

Figure 3 is a bottom plan view of the bobsled, showing my new design.

Figure 4 is a rear end view of the bobsled, showing my new design.

I claim:

The ornamental design for a bobsled, as shown.

RALPH WARRENDER.
